UNITED STATES PATENT OFFICE.

OTTO SCHWALB, OF JERSEY CITY, NEW JERSEY.

BELT CLASP.

Application filed September 14, 1925. Serial No. 56,104.

This invention relates to belt clasps, and more particularly to a device of the clamping type wherein there is provided a pivoted clamping member to tightly grip and clamp the belt end against the front plate of the clasp.

It is the primary object and purpose of the present improvements to provide a supporting element mounted for relative swinging movement on the pintle of the pivoted clamping member and adapted for engagement through a loop on one front edge of the trousers so as to sustain the same against sagging relative to the underlying edge portion of the trousers.

It is another object of the invention to provide an improvement in belt clasps of the above character which is exceedingly simple and will not, therefore, materially add to the manufacturing cost of such devices.

With the above and other objects in view, the invention consists in the improved belt clasp, and in the form, construction and relative arrangement of its several parts as will be hereinafter more fully described, illustrated in the accompanying drawings, and subsequently incorporated in the subjoined claims.

In the drawings, wherein I have illustrated one simple and practical embodiment of the invention, and in which similar reference characters designate corresponding parts throughout the several views,—

Figure 1 is a front elevation showing my improved belt clasp as applied in use;

Fig. 2 is a longitudinal section taken on the line 2—2 of Fig. 1, and

Fig. 3 is a rear elevation of the clasp.

Referring in detail to the illustrated embodiment of the device, the front or face plate 5 is preferably of concavo-convex form and may be of any desired size and shape. On its opposite side edges, this plate is provided with rearwardly projecting lateral flanges 6, each of which is formed with an inturned longitudinally tapering flange 7 spaced from the inner side of the face plate and providing guiding and retaining means for the belt end. In lugs, ears or other suitable means indicated at 8 provided on the widely spaced ends of the flanges 7 the ends of a pintle 9 are fixed. A loop 10 is provided with spaced lugs 11 loosely engaged upon said pintle, and to said loop, one end of the belt 12 is suitably attached.

The clamping member 13 is in the form of an elongated plate extending transversely of the clasp and having a serrated face for engagement with the inner surface of the free end of the belt as clearly shown in Fig. 2 of the drawings. This clamping member is formed with a central lug 14 which is loosely engaged upon the pintle 9 between the lugs 11 of the loop 10. The clasp construction as thus far described is well known in the art and constitutes no essential part of my present improvements, and it will be understood that the form, construction and mounting of the front or face plate and the loop 10 and clamping member 13 might be variously modified.

The novel feature of my improvements consists in the provision of a supporting element 15 which in the present instance is illustrated in the form of a hook constructed from a length of wire having its end portions spaced apart as at 16 and terminating in eyes loosely swiveled on the pintle 9 between the lug 14 of the clamping member and the lugs 11 of the loop 10 so that said element may freely swing or turn on the pintle relative to said loop and clamping member. The hook bill 17 formed in the intermediate portion of said wire is laterally directed, and as will be noted from reference to Figs. 1 and 3 of the drawing, this hook bill limits the swinging movement of the element 15 in one direction by contact upon one of the belt guiding flanges 7 of the clasp plate so that said hook bill cannot move inwardly of said flanges and against the inner face of the plate. The supporting element 15 includes an intermediate portion 20 of a length substantially equal to the width of the loop 19 on the trousers, and two laterally projecting portions 21 and 22 extending substantially at right angles from the intermediate portion. This construction of the supporting element operates to prevent relative shifting of the supporting element and the loop 19 when the device is applied. Preferably the part 21 extends at a slightly acute angle from the intermediate part 20 to more effectively retain the supporting element in connection with the loop 19 and prevent the casual disengagement of said loop from the hook bill 17.

In the use of the device as above described, the belt is passed through the usual straps or loops 18 on the upper edge of the trousers and the clasp positioned upon the overlap-

ping front edges of the trousers. The outermost front edge portion of the trousers is provided with a relatively small loop 19 thereon and through this loop the hook bill 17 of the supporting element 15 is inserted, said hook bill projecting upwardly as seen in Fig. 1 of the drawings. The free end of the belt is then passed between the front plate of the clasp and the guide flanges 7 thereon and between said plate and the clamping member 13 and its extremity inserted through one of the straps or loops 18 on the trousers and said free end of the belt pulled so that the pivoted clamping member 13 will 15 exert a gripping pressure thereon in the usual manner and tightly clamp the belt end against the inner side of the front or face plate 5. It will thus be seen that in addition to supporting the trousers by circumferential constricting pressure of the belt, the supporting hook 15 engaged through the loop 19 sustains the overlapping front portions of the trousers against sagging or buckling so that these overlapping edges will not present a disorderly appearance to the dress of the wearer.

From the foregoing description considered in connection with the accompanying drawing, the construction of my present invention as well as the several advantages thereof will be clearly and fully understood. It will be seen that I have devised a very simple improvement in such belt clasps which will materially increase the utility thereof. Since the construction of the trousers supporting or sustaining element is exceedingly simple and may be readily applied to such belt clasps as heretofore manufactured, it will be appreciated that my improvement will not materially add to the manufacturing or selling cost of the article. While I have referred to this supporting element as formed from a length of wire, it will nevertheless, be understood that the same advantages may be obtained by constructing this element of other materials and in various other forms than that illustrated in the drawing. It is, therefore, to be

understood that I reserve the privilege of resorting to all such legitimate changes in the construction of the device as may be fairly embodied within the spirit and scope of the invention as claimed.

I claim:

1. A belt clasp comprising a front plate having belt guiding flanges projecting inwardly in spaced relation to the rear side of said plate, a belt attaching loop and a belt clamping member pivotally supported by said flanges, and a supporting element pivotally mounted at one of its ends for swinging movement independently of said loop and the clamping member and terminating at its other end in a hook adapted for insertion through a loop on the trousers or other article of wearing apparel, and said hook projecting over one of said flanges and limited thereby in its swinging movement towards the rear side of said front plate, said supporting element having spaced parts disposed substantially parallel to said pintle and between which the trousers loop is engaged with said element and whereby said loop and the supporting element are prevented from shifting relative to each other longitudinally of the clasp.

2. A belt clasp comprising a front plate having a fixed pintle mounted on the rear side thereof adjacent one end of the plate, a belt attaching loop and a belt clamping member pivoted on said pintle for independent swinging movement, a trousers supporting element swiveled on the pintle for swinging movement independently of the loop and the clamping member and adapted to be engaged through a loop on the trousers to support the same against sagging, and stop means limiting the swinging movement of said supporting element to a position in spaced relation to the rear side of said plate on the trousers.

In testimony that I claim the foregoing as my invention, I have signed my name hereto.

DR. OTTO SCHWALB.
